TAPE FOR SLIDE FASTENERS

Lester L. Jones, Oradell, N. J., assignor to Conmar Products Corporation, Newark, N. J., a corporation of New Jersey

Application October 21, 1941, Serial No. 415,899

18 Claims. (Cl. 139—384)

This invention relates to slide fasteners, and more particularly to fabric tape for the same.

Conventional slide fasteners comprise a series of elements having jaws which are clamped on the beaded edge of a fabric tape. The prevailing practice for making the beaded edge on the tape is to stitch two separate cords on opposite sides of a flat tape near one edge thereof. This practice has a number of disadvantages. One is the need for special sewing machines and guides, and the expense of the extra sewing operation. Another is the need for properly adjusting the tension so that the tape will remain straight, or will have a slight concavity at the beaded edge. The sewing operation is commonly performed by the slide fastener manufacturer, and this makes it necessary to purchase cords and sewing machine thread of exactly the same color as the tape, the latter being dyed by the tape manufacturer. This color problem is serious because of the large number of differently colored tapes required for the garment industry.

The primary object of the present invention is to generally improve tapes for slide fasteners, and a more specific object is to provide an integrally woven tape, that is, a tape having a satisfactory bead formed as a part of the operation of weaving the tape, and prior to the dyeing operation.

A number of proposals have heretofore been made for integrally weaving a bead on a tape. These tapes have for the most part used a woven sleeve enclosing a cord or stuffing to form the bead. Such a tape has not proved satisfactory, as it does not provide as good a hold for the elements as a tape with two cords, and is relatively stiff.

Even with two cords held in position by the regular weft threads of the tape, there is the disadvantage of exposing the weft threads to abrasion by the jaws of the fastener elements, and in some cases even to abrasion by the slider. Wear or tearing of the weft threads releases the cords and consequently the fastener elements.

It is accordingly a particular object of the present invention to overcome the foregoing faults and disadvantages of prior tapes with integral beads. Other objects of my invention are to provide a tape having a bead of adequate bulk yet which does not interfere with free flexibility of the tape; to provide a tape having cords which actually shield and protect the weft threads from abrasion by the fastener elements, instead of exposing the same to increased abrasion; to provide a beaded edge which is relatively soft

and well adapted to accommodate and to conform to the interior of the jaws of the fastener elements; to provide a tape having an integrally woven beaded edge which is stronger under destruction tests, than conventional sewed cords; to provide a tape which will be more uniformly gripped by the successive fastener elements; and finally, to provide a tape the cords of which are readily separable from the tape at one end

10 when making a fully separable slide fastener.

To accomplish the foregoing and such other objects as will hereinafter appear, my invention consists in the beaded tape elements and their relation one to the other, as hereinafter are 15 more particularly described in the specification and sought to be defined in the following claims. The specification is accompanied by a drawing in which:

Fig. 1 is a section through the beaded edge of 20 a tape, taken between fastener elements, prior to clamping of the jaws of the fastener element;

Fig. 2 is a similar view showing the relation of 25 the parts after the jaws of the fastener element have been closed;

Fig. 3 is an elevation looking at the beaded 30 edge of the tape;

Fig. 4 is a schematic sectional view taken approximately in the plane of the line 4—4 of 35 Fig. 3;

Fig. 5 is a schematic sectional view taken approximately in the plane of the line 5—5 of Fig. 3;

Fig. 6 is an elevation looking at the beaded 40 edge of a modified form of tape employing a leno weave;

Fig. 7 is a side elevation of the tape shown in 45 Fig. 6;

Fig. 8 is a view similar to Fig. 6, but with the 50 cords separated to show the construction or weave of the tape;

Fig. 9 is explanatory of a modified construction; and

Fig. 10 shows the direction of preferred curvature of the tape.

Referring to the drawing, and more specifically to Figs. 1 and 2, the principle underlying the present invention may be explained by bringing out the fact that the beaded edge of my invention employs not only buffer cords 18 at each side of the tape, but also an anchor cord 12 which is disposed at the very edge of the tape and is securely woven therein by the weft threads 14. The buffer cords 18 are located adjacent to the anchor cord 12. The plane through the axes of the buffer cords should pass on the tape side of the

axis of the anchor cord, the latter being a part of the tape web and its principal function being to hold the tape web against escape after the slide fastener elements have been clamped in position. The closing of the fastener element jaws 16 from the open position shown in Fig. 1 to the closed position shown in Fig. 2, compresses the buffer cords 10 so that they conform to the inside of the jaws 16. The buffer cords hold the tape web or the anchor cord 12 against escape. It is important to provide means to hold the buffer cords in position, so that the tape may be treated and handled as a one-piece tape during its weaving, dyeing, and subsequent handling in the slide fastener plant. A number of important advantages of my construction will be apparent, for the weft threads are protected against injury by the buffer cords, hence the anchor cord or the tape web of which it is a part is securely held against escape. The use of three cords to build up the desired bulk incidentally but importantly results in a relatively flexible beaded edge.

The anchor cord, while substantially larger in diameter than the regular warp threads 18 of the tape, is preferably smaller than the buffer cords 10. It is also harder than the buffer cords, as for example, by using a cord of greater twist than that of the buffer cords. The buffer cords are relatively larger in diameter, and are relatively soft, as for example, by using cords with only a moderate amount of twist. The buffer cords are preferably twisted in opposite directions, as shown in Fig. 3, in order to avoid or minimize any tendency of the finished slide fastener to twist.

The means to hold the buffer cords on the tape may vary. In Figs. 3, 4 and 5 I show a preferred construction in which the buffer cords 20 are held by spaced weft threads 22. The remainder and by far the greater number of weft threads 24 pass around the anchor cord 26, as is clearly shown in Fig. 4, but do not pass around the buffer cords 20. However, at intervals one of the weft threads passes around the buffer cords 20, as is shown in Fig. 5, but does not pass around the anchor cord 26.

In the specific case here illustrated, every fourth weft thread is employed to hold the buffer cords, while three out of four weft threads are employed to hold the anchor cord. The number of threads used to hold the buffer cords may be varied, but I believe that one in four is a preferred amount. If a greater number of weft threads is used to hold the buffer cords, as for example, if every third thread is used to hold the buffer cords, the tape proves weaker when subjected to destruction tests. This is no doubt due to the exposure of a greater number of weft threads to abrasion and wear, and a reduction in the number protected against wear. If a lesser number of threads is used to hold the buffer cords, as for example, if one thread in five is used for that purpose, the buffer cords tend to become too loose on the tape, from the viewpoint of easy handling, as for example, when pulling the tape through the closely fitting die of the attaching machine which clamps the elements on the tape. The cords may creep (hold back) or roll relative to the tape body. Of course, the quantitative ratio may vary with the closeness of the particular weave under consideration and the strength and tension of the weft threads used, etc., and I may therefore point out in a general way that the optimum number of weft threads to be used for holding the buffer cords in position should be rel-

atively small, on the one hand, in order to minimize the exposure of weft threads to abrasion, and on the other hand, should not be so small as to create an inconvenient looseness of the buffer cords making the same difficult or inconvenient to handle during attachment of the fastener elements.

In Figs. 6, 7 and 8, I show a modification of the invention in which the buffer cords are disposed outside of all of the weft threads, or in other words, in which all of the weft threads pass around the anchor cord alone, and none pass around the buffer cords. To hold the buffer cords in position, prior to clamping of the elements on the tape, several of the warp threads are given a leno weave, that is, they are passed through a heddle which is arranged for sideward movement in order to transpose the thread at intervals, as will be understood by those skilled in the weaving art. Thus, referring to Figs. 6 and 7, the anchor cord 28 is held by all of the regular weft threads, these being indicated at 30. The buffer cords 32 and 34 are held by leno woven threads 36 and 38, respectively. This construction will be clearer from inspection of Fig. 8, which is like Fig. 6 except that the parts have been spaced to expose the weave employed, that is, the buffer cords 32 and 34 have been pulled away from the tape and the anchor cord 28. This exposes the course of thread 36, which is a warp thread located at the right-hand side of the tape, but passing through the tape to the left and around the buffer cord 32 at intervals, which in this case are spaced by four weft threads. Similarly, the leno thread 38 is located at the left-hand side of the tape, but passes to the right through the tape at intervals to form loops around the buffer cord 34. It will be understood that the leno woven threads 36 and 38 are disposed in back of the anchor cord, and that when these threads are pulled taut the buffer cords 32 and 34 will be drawn in against the sides of the tape immediately at the anchor cord. The buffer cords are shown twisted in like direction, and opposite to the twist of the anchor cord, the latter theoretically counteracting the former, but in practice the oppositely twisted buffer cords shown in Fig. 3 seem to work better, and I therefore prefer the latter.

Another illustration of a leno woven construction is shown in Fig. 9, which is a schematic view looking at one side of the tape. In this view only one buffer cord and leno thread are shown, but it will be understood that a similar buffer cord and leno thread are provided on the opposite side of the tape. In Fig. 9, all of the weft threads 42 pass around the anchor cord 40. There are additional warp threads immediately back of the anchor cord 40, as is indicated by the thread 44 or 46, or both. As a matter of fact, in all of the constructions shown, the warp threads may run right up to the anchor cord, and a few of them may be disposed between the buffer cords even though the schematic illustrations in the drawing may tend to create the impression that there is no tape material separating the buffer cords. In Fig. 9, the nearer buffer cord is indicated at 48, and this is held by loops 50 of a leno woven thread 52. It will be observed that the leno woven thread 52 is linked with the weft threads 42 with an in-and-out weave. This helps keep the vertical or relatively straight parts of the leno thread in proper position between the horizontal loops 50, so that the leno thread acts as a true warp thread forming a part of the body of the

tape. A similar leno woven thread is provided for the opposite buffer cord.

The maximum dimension of the three-cord edge should be small enough to fit between the spread jaws of the element before the jaws are closed. It is desirable, for example, that the element when being fed to the tape should not roll the buffer cords back away from the edge of the tape. On the other hand, the total mass of the two buffer cords, the anchor cord, the few warp threads between the buffer cords, and the weft threads, or in other words, the total mass of the fabric inside the element jaws, should be big enough to provide a firm attachment when the jaws are clamped on the tape. Another dimensional requirement is that the anchor cord should be big enough to really anchor the tape to the elements. More specifically, the anchor cord should be bigger in diameter than the space between the tips of the clamped jaws. Of course, the effective diameter of the anchor cord is somewhat larger than its actual diameter, in that the weft threads are wrapped closely therearound and help enlarge the same. The buffer cords should be large enough and so located that when they are squeezed down by the jaws of the elements, they should nearly completely envelope the weft threads in order to protect the same. In respect to their location, the buffer cords should be close to the anchor cord, rather than far back of the same, for in the latter case the weft threads wound about the anchor cord would be largely exposed to abrasion by the fastener elements.

The tape is preferably given a slight initial concavity at the beaded edge, as is schematically indicated in Fig. 10. This is desirable because the beaded edge is lengthened somewhat when the elements are clamped thereon, thus providing a finished fastener which is straight, and which, if it departs from being straight, is preferably concave rather than convex at the elements, because the latter produces a so-called "bumpy" fastener.

To produce the desired initial concavity, the cords of the beaded edge are preferably stretched or placed under a higher tension than the regular warp threads during the weaving operation. The thus initially stretched threads tend to contract when the tape leaves the loom, and so produce the desired concavity. The tension applied to the cords should be considerably higher than that applied to the warp threads.

It is also important that the buffer cords be held tightly to the anchor cord and tape, because otherwise, the buffer cords may tend to become excessively loose, permitting them to be displaced from proper position before or during the attachment of the elements. It is important that the jaws be clamped around all three cords, and it is further desirable that the buffer cords be held so close to the anchor cord that they will be compressed around the anchor cord and thereby protect the otherwise exposed loops of weft thread around the anchor cord.

It is believed that the improved tape of my invention, as well as the many advantages thereof, will be apparent from the foregoing detailed description. The weft threads are protected against abrasion by the fastener elements. The beaded edge of the tape is very flexible. The beaded edge is soft enough to conform readily to the inside shape of the element jaws. The many disadvantages of sewed cords are eliminated.

One specific advantage of the present tape arises in connection with the manufacture of fully separable slide fasteners, that is, slide fasteners

having a separable bottom stop for use on coats or other applications where the two sides of the fastener must be entirely separable from one another. In manufacturing such a fastener, it is customary to reversely fold the lower ends of the tape before securing the halves of the separable bottom stop thereto. However, to avoid excessive bulk of fabric at the beaded edge, the cords are removed from the reversely folded end of the tape. This has been a tedious and difficult job with prior tape constructions, but is readily accomplished with the present tape, for the buffer cords are relatively loosely held in position by only a few spaced loops of thread.

Before closing, it may be pointed out that while I have illustrated the invention in simplest form employing a single anchor cord and two buffer cords, it is theoretically possible to practice the invention while using a plurality of smaller anchor cords instead of one large anchor cord, or a plurality of smaller buffer cords on each side of the tape, instead of a single large buffer cord, the important thing being, of course, that all or most of the weft threads are to pass around the anchor cords alone, but not around the buffer cords, the latter being held mainly by the clamped jaws of the fastener elements, although preliminarily held on the tape by appropriate means, such as a spaced fraction of the weft threads, or warp threads woven with a leno weave.

It will be apparent that while I have shown and described my invention in several preferred forms, many changes and modifications may be made in the structures disclosed, without departing from the spirit of the invention as sought to be defined in the following claims.

I claim:

1. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover.

2. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, said buffer cords being located outside most or all of the weft threads and helping to protect the same against abrasion by the jaws.

3. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, and means to hold the buffer cords in position until the jaws of the fastener elements are clamped thereover, said buffer cords being located outside most or all of the weft threads and helping to protect the same against abrasion by the jaws, said buffer cords being relatively soft and large in diameter, and said anchor cord being relatively hard and smaller in diameter although

substantially larger than the regular warp threads of the tape.

4. A tape for slide fasteners of woven warp threads and weft threads, said tape comprising an anchor cord held at one edge by weft threads, a buffer cord on each side of the tape, the plane through the axes of said buffer cords passing on the tape side of the axis of but very close to the anchor cord, said anchor cord being substantially larger than the regular warp threads of the tape, and means to hold the buffer cords in position until the jaws of the fastener elements are clamped thereover, said buffer cords being located outside most or all of the weft threads and helping to protect the same against abrasion by the jaws, said buffer cords being relatively lightly twisted, and said anchor cord being relatively tightly twisted.

5. A tape for slide fasteners of woven warp threads and weft threads, said tape comprising an anchor cord held at one edge by weft threads, a buffer cord on each side of the tape, the plane through the axes of said buffer cords passing on the tape side of the axis of but very close to the anchor cord, and means to hold the buffer cords in position until the jaws of the fastener elements are clamped thereover, the maximum dimension of the resulting three-cord edge being small enough to fit between the spread jaws of the fastener element before the jaws are clamped together, but the total mass of the fabric within the jaws being large enough to provide a firm attachment when the jaws are clamped together, and the anchor cord being larger in diameter than the space between the tips of the clamped jaws.

6. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, said means consisting of rather widely spaced weft threads which run about the buffer cords but not about the anchor cord, the intervening and numerically greater number of weft threads passing about the anchor cord but not about the buffer cords.

7. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, said means consisting of every fourth weft thread, said fourth weft thread passing about the buffer cords but not about the anchor cord, and the intervening three out of four weft threads passing about the anchor cord but not about the buffer cords.

8. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, and means to hold the buffer cords in position until

the jaws of the fastener elements are clamped thereover, said buffer cords being located outside most of the weft threads and helping to protect the same against abrasion by the jaws, said buffer cords being relatively soft and large in diameter, said anchor cord being relatively hard and smaller in diameter although substantially larger than the regular warp threads of the tape, the anchor cord being larger in diameter than the space between the tips of the clamped jaws, the aforesaid means for holding the buffer cords in position consisting of rather widely spaced weft threads which run about the buffer cords but not the anchor cord, the intervening and numerically greater number of weft threads passing about the anchor cord but not the buffer cords.

9. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, and means to hold the buffer cords in position until the jaws of the fastener elements are clamped thereover, said buffer cords being located outside most of the weft threads and helping to protect the same against abrasion by the jaws, said buffer cords being relatively soft and large in diameter, said anchor cord being relatively hard and smaller in diameter although substantially larger than the regular warp threads of the tape, the anchor cord being larger in diameter than the space between the tips of the clamped jaws, the aforesaid means for holding the buffer cords in position consisting of every fourth weft thread, said fourth weft thread passing about the buffer cords but not the anchor cord, and the intervening three out of four weft threads passing about the anchor cord but not the buffer cords.

10. A tape for slide fasteners of woven warp threads and weft threads, said tape comprising an anchor cord held at one edge by weft threads, a buffer cord on each side of the tape, the plane through the axes of said buffer cords passing on the tape side of the axis of but very close to the anchor cord, said anchor cord being substantially larger than the regular warp threads of the tape, and means to hold the buffer cords in position until the jaws of the fastener elements are clamped thereover, said buffer cords being located outside most of the weft threads and helping to protect the same against abrasion by the jaws, said buffer cords being relatively soft and large in diameter, said anchor cord being relatively hard and smaller in diameter although substantially larger than the regular warp threads of the tape, the anchor cord being larger in diameter than the space between the tips of the clamped jaws, the aforesaid means for holding the buffer cords in position consisting of every fourth weft thread, said fourth weft thread passing about the buffer cords but not the anchor cord, and the intervening three out of four weft threads passing about the anchor cord but not the buffer cords.

11. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, said means consisting of warp threads twisted leno fashion about the cords whereby the buffer

cords are disposed outside of all of the weft threads.

12. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, said means consisting of warp threads transposed at intervals over the buffer cords and linked or interwoven with the weft threads after each transposition, whereby the buffer cords are disposed outside of all of the weft threads and help protect the same against abrasion by the jaws of the fastener elements.

13. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, and means to hold the buffer cords in position until the jaws of the fastener elements are clamped thereover, said buffer cords being relatively soft and large in diameter, said anchor cord being relatively hard and smaller in diameter although substantially larger than the regular warp threads of the tape, the aforesaid means for holding the buffer cords in position consisting of warp threads twisted "leno" fashion about the cords, whereby the buffer cords are disposed outside of all of the weft threads.

14. A tape for slide fasteners of woven warp threads and weft threads, said tape comprising an anchor cord held at one edge by weft threads, a buffer cord on each side of the tape, the plane through the axes of said buffer cords passing on the tape side of the axis of but very close to the anchor cord, and means to hold the buffer cords in position until the jaws of the fastener elements are clamped thereover, said buffer cords being relatively soft and large in diameter, said anchor cord being relatively hard and smaller in diameter although substantially larger than the regular warp threads of the tape, the aforesaid means for holding the buffer cords in position consisting of warp threads transposed at intervals over the buffer cords and linked or interwoven with the weft threads after each transposition, whereby the buffer cords are disposed outside of all of the weft threads and help protect the same against abrasion by the jaws of the fastener elements.

15. A tape for slide fasteners of woven warp threads and weft threads, said tape comprising an anchor cord held at one edge by weft threads, a buffer cord on each side of the tape, the plane through the axes of said buffer cords passing on the tape side of the axis of but very close to the anchor cord, said anchor cord being substantially larger than the regular warp threads of the tape, and means to hold the buffer cords in position until the jaws of the fastener elements are clamped thereover, said buffer cords being relatively

tively lightly twisted, and said anchor cord being relatively tightly twisted, the aforesaid means for holding the buffer cords in position consisting of warp threads transposed at intervals over the buffer cords and linked or interwoven with the weft threads after each transposition, whereby the buffer cords are disposed outside of all of the weft threads and help protect the same against abrasion by the jaws of the fastener elements.

16. A slide fastener comprising a tape of woven warp threads and weft threads having a corded edge and a series of fastener elements having jaws clamped around the corded edge of the tape, the tape comprising an anchor cord held by the weft threads of the tape, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, the clamped jaws of the fastener elements operating to compress the buffer cords around the anchor cord so as to largely envelope and thereby protect the loops of weft thread around the anchor cord from abrasion by the jaws of the fastener elements.

17. A tape for slide fasteners of woven warp threads and weft threads, said tape comprising an anchor cord held at one edge by weft threads, a buffer cord on each side of the tape, the plane through the axes of said buffer cords passing on the tape side of the axis of the anchor cord, said anchor cord being substantially larger than the regular warp threads of the tape, and means to hold the buffer cords in position until the jaws of the fastener elements are clamped thereover, said anchor cord and buffer cords being woven under considerably higher tension than the regular warp threads, whereby said tape is given a slight concavity at the corded edge.

18. A slide fastener comprising a tape of woven warp threads and weft threads having a corded edge and a series of fastener elements having jaws clamped around the corded edge of the tape, the tape comprising an anchor cord held at one edge of the tape by weft threads of the tape, said anchor cord being substantially larger than the regular warp threads of the tape, a buffer cord on each side at the anchor cord, the buffer cords being received within the jaws of the fastener elements, and means to hold the buffer cords in position prior to clamping of the jaws of the fastener element thereover, said means consisting of rather widely spaced weft threads which run about the buffer cords but not the anchor cord, the intervening and numerically greater number of weft threads passing about the anchor cord but not the buffer cords, the clamped jaws of the fastener elements compressing and spreading the buffer cords around the anchor cord so as to largely envelope and thereby protect the loops of weft thread around the anchor cord from abrasion by the jaws of the fastener elements.

LESTER L. JONES.
